UNITED STATES PATENT OFFICE.

JULIUS KUNZE, OF YONKERS, NEW YORK.

HAND PRINTING-PRESS.

SPECIFICATION forming part of Letters Patent No. 401,839, dated April 23, 1889.

Application filed January 21, 1888. Serial No. 261,503. (No model.)

To all whom it may concern:

Be it known that I, JULIUS KUNZE, a citizen of the United States, and a resident of Yonkers, Westchester county, State of New

5 York, have invented certain new and useful Improvements in Hand Printing-Presses, of which the following is a specification.

This invention relates to hand printing-presses, and has for its objects to adapt such 10 presses to be used in a cold or heated condition, to provide ready means whereby the heated parts may be quickly cooled off, and by improvements generally in the construction to facilitate the operation thereof.

15 My improved press comprises a suitably-formed frame, a plunger fitted in guides and moving vertically therein, a hand-lever for actuating the plunger, a pivoted bifurcated lever controlled by a spring at one end and 20 connected at its other ends to the plunger for raising the same, an impression bed or table fitted in ways on the frame so as to slide under the plunger at right angles thereto; a gas-burner head secured to the head of the plunger, 25 a die-holder secured to the gas-burner head, and an ink-roller carried by the sliding impression bed or table.

To more fully describe the construction and 30 operation of the press, I will now refer to the accompanying drawings, forming part of this specification, in which—

Figure 1 is a perspective view of a press embodying my improvements. Fig. 2 is a 35 perspective view of the gas-burner head and die-holding head detached. Fig. 3 is a perspective view of the die-holding head detached. Fig. 4 is a transverse vertical section of the upper part of the press. Fig. 5 is 40 a longitudinal vertical section of the same; and Fig. 6 is a section of the head on the line $x x$, Figs. 4 and 5.

The main frame a is provided with the vertical guides b , adjusted by the screws b' , and the horizontal guides or ways c . In the 45 guides b is fitted to slide the plunger d , having on its lower end the circular head d' , and provided with the adjustable screw-seat e , between which and the notch f' of the hand-lever f is held the thrust-rod e' . This hand-lever f is pivoted at g in the upper part of the 50 frame a , and is provided with an adjustable

stop, g' , which determines the limit of its downward movement by coming in contact with the elastic seat g^2 , set in the side of the frame a .

55 The device for raising the plunger d consists of the bifurcated lever h , resting on the arm a' , projecting from the frame as a fulcrum-bearing, the spring h' , connected by an eye to the side of the side frame and by 60 means of a nut on its upper end to the outer end of the lever h , and the rods h^2 , which are screwed in the heads of the plunger d and set on the inner ends of the lever h by means of eyes formed in their upper ends. These 65 rods are set at an angle to facilitate the manipulation of the screw-seat e in adjusting the impression.

The gas-burner head i , circular in form, is 70 hollow, and is provided with the dovetail rib i' , projecting above the edge of its wall, in which wall are the orifices i^2 , i^3 and dividing the inside of the head into two chambers. This dovetail rib fits into a groove formed in the bottom of the head d' of the plunger, 75 extending only partly through the same. To the plunger d at the rear end of the dovetail groove is connected the gas-pipe j , as clearly shown at Fig. 4. From the hole d^2 , in which the gas-pipe is connected to the plunger, two 80 angular passages extend to the bottom of the head of the plunger, the outlets of said passages being over the chambers in the gas-burner head i , as clearly shown in Fig. 6.

The bottom of the gas-burner head i , which 85 is flat and projects beyond the wall provided with the orifices i^2 , i^3 , has formed in it a dovetail groove, into which fits the dovetail rib k' on the die-head k . This die-head carries the die l , secured thereto by means of the screw 90 l' , thereby providing for the ready removal and replacement of the die l from and on the head k .

To securely fasten the gas-burner head and die-head in place, a screw, m , is fitted to pass 95 through the head d' of the plunger d , through the gas-burner head i , and into the die-head k , as shown at Fig. 4.

The impression bed or table n , fitted to slide on the ways c , is of the ordinary construction. 100 It is provided at its rear end with bearings o' , in which rests the ink-roller o , so arranged

as to roll in contact with the die *l* when the bed *n* is pulled forward in position to receive a sheet of the material to be impressed.

The operation of this class of printing-press 5 is generally understood, so it will only be necessary here to describe the manipulation of the movable heads and the action of the heating device. The gas entering the two chambers in the head *i* through the gas-pipe *d*² and 10 passages *d*³ *d*³ issues therefrom at the orifices *i*² *i*², and upon being ignited heats the head *d'* of the plunger and burner-head *i* uniformly, and by conduction also heats the die-head *k* and die *l*, attached thereto. By this 15 arrangement the die is regularly heated and maintained at a constant temperature.

It is often advantageous to be able to do cold printing on a machine immediately after a part of the work or another job has been 20 run off the press while in a heated condition. This I provide for by the burner and die-heads being so constructed as to be readily removed from the press, which is accomplished by backing up the screw *m* until it clears the 25 burner-head, inserting the handle or bar *p* in the screw-hole at the front of the burner-head, drawing it out from the plunger-head, as shown at Fig. 2, and then cool the detached heads by spraying them with or dipping them 30 in water, after which they may be set back in the press with the same die or another one, as desired, secured to the die-head. If it is required to remove the die-head only to cool it, for an exchange of dies, or for an examination 35 of the die attached thereto, then the screw *m* need only be unscrewed to clear said head, and the handle *p* inserted in the screw-hole at the front thereof, when it may be removed from the gas-burner head, as shown at Fig. 3. 40 Having now described my invention, what I claim, and desire to secure by Letters Patent, is—

1. The combination, with the plunger of a printing-press, of a hollow gas-burner head detachably secured thereto, said plunger having gas-passages opening into the hollow head, and said hollow head having orifices in its sides, through which the gas escapes, and when ignited impinges against the bottom of the plunger. 45

2. In a printing-press, in combination, a plunger having a circular head and a dovetail groove in the under side thereof, a hollow gas-burner head having orifices through its side and provided with a central dovetail rib 50 adapted to fit in the groove of the plunger-head and a dovetail on its under side, and a die-head provided with a dovetail rib adapted to fit in the groove at the under side of the gas-burner head. 55

3. In a printing-press, in combination, a plunger having a circular head, with a dovetail groove formed partly through the under side thereof, a gas-pipe secured thereto, and passages from the pipe extending through the 60 bottom at either side of the groove, a hollow gas-burner head provided with orifices through its side and having a central rib dividing it into two chambers and projecting above it in the form of a dovetail to fit the groove in the 65 plunger-head, a die-head provided with a dovetail rib adapted to fit in a groove in the under side of the gas-burner head, a die secured to the die-head by means of a central screw, and a locking-screw passing through 70 the plunger-head and the gas-burner head into the die-head. 75

Signed at New York, county and State of New York, this 19th day of January, A. D. 1888.

JULIUS KUNZE.
